UNITED STATES PATENT OFFICE.

LUES REITER AND HARRY FULFORD, OF PROVIDENCE, RHODE ISLAND.

SEPARABLE FASTENER

1,150,623.

Specification of Letters Patent. Patented Aug. 17, 1915.

Application filed July 14, 1913. Serial No. 778,870.

To all whom it may concern:

Be it known that we, LUES REITER and HARRY FULFORD, citizens of the United States, and residents of the city of Providence, in the county of Providence and State of Rhode Island, have invented certain new and useful Improvements in Separable Fasteners, of which the following is a specification.

- 10 This invention relates to a socket member for separable fasteners, and has for its object to provide a simple and practical socket of inexpensive construction, the same comprising a front plate of concavo-convex
15 shape having a central opening and split through its face, said plate being hardened and made resilient by swaging, the edge of said plate being bent back substantially upon itself and provided with a plurality of
20 closely set fingers providing a neck portion adapted to pass through the goods to which it is to be attached said socket being thus adapted to receive and removably secure a complemental stud.

25 A further object of the invention is to provide an annular rib or projecting portion around the underside of the periphery of the front plate whereby when the socket is secured to the goods this rib will be forced 30 and set into the goods to more securely retain the goods to the socket when attached thereto.

The invention further consists in the provision of a hollow securing cap having an opening into which the ends of said fingers are passed and spread for securing the socket to said cap and at the same time securing both said socket and cap to the goods.

With these and other objects in view, the invention consists of certain novel features of construction, as will be more fully described and particularly pointed out in the appended claim.

45 Of the accompanying drawings: Figure 1—is an enlarged sectional elevation showing the socket member permanently secured to the material or goods by means of a cap into which its fingers are clenched and also showing the engaging stud in position to enter the socket. Fig. 2—is a plan view showing the shape of the blank from which the socket member is formed. Fig. 3—is a central sectional elevation on line 3—3 of Fig. 4, showing the blank as having been 50 drawn up into substantially a cup-shape and showing the face plate as split by striking

one portion thereof below the plane of the other. Fig. 4 is a bottom plan view of the blank after it has been struck into cup-shape as shown in Fig. 3. Fig. 5—shows the blank with the fingers drawn partly inward. Fig. 6—shows the fingers drawn inward until their edges meet forming a contracted neck portion, also showing the middle opening through the face and the under edge of the periphery rolled inward to form an annular rib. Fig. 7—is a plan view from the underside of the socket. Fig. 8—is a plan view of the face of the socket. Fig. 9—is a view of the under side of the cap member. 60

70

Referring to the drawings our improved socket member is preferably formed from a single piece of comparatively soft sheet metal, the same being provided with a plurality of fingers 10, any suitable number being employed, the number of fingers herein shown being five. The next operation after forming the metal blank as illustrated in Fig. 2 is to draw the same up into substantially a cup form, as illustrated in Fig. 3, with the fingers 10 extending outwards, as shown, and the fingers being bent over to hold the cup member 70. 75. 80.

3, with the fingers 10 extending at substantially right angles to the plane of the front plate 11, this front plate being at the same time struck by a cutter so as to break, pierce or shear the stock providing two short radial slits 12—12 extending from the edge inward a short distance. The face plate is then struck a number of times forming the same into concavo-convex shape forming an annular groove 13 in its face adjacent the edge thereof. This hammering or swaging action in addition to shaping the face plate into the desired form, also hardens the stock so that

when the center portion 14 is removed from the plate a pair of resilient lips 15 are provided which will spring and open slightly to receive the stud 6 of the other portion of the fastener shown in Fig. 1. The edge of this front plate is then rolled over as illustrated at 25 in Fig. 6 forming an annular bead or rib 16 around its under edge. The fingers 10 are also carried inward toward each other until their adjacent edges meet near their ends, thereby providing a contracted neck portion 17 adapted to be passed through a hole formed in the goods and fastened in the cap in the manner herein-after described. The bending and shaping of these fingers about their base portion hardens the same for a portion of their length and forms a neck of stiff resilient material that will withstand the strains re-

quired of it, at the same time the end portions of these fingers are left in their original soft, ductile, and pliable condition by reason of their not having been hammered or swaged, whereby they may be readily bent in securing the socket to the goods as presently described. As a suitable means for readily securing this socket to the goods I have provided a cap member 18, see Figs. 10 1 and 8, the same being substantially in the form of a hollow flattened button head with a hardened plate or washer 19 inclosed within the same, said washer being provided with an engaging face 22 somewhat beveled 15 from its center portion outward all around to its outer edge, said washer being rolled into the cap member, the rear face 20 of said cap being provided with a central opening 21. In securing this improved socket member to the goods a hole is punched in the latter through which the neck portion 17 of the socket member is passed. The cap member is then placed against the opposite side of the goods and the ends of the fingers 25 extend into its central opening and rest against the beveled face of the washer so that by exerting a pressure by means of a pair of pliers or other suitable device or instrument the soft and ductile ends of the 30 fingers open and spread and are forced outward under the rear edge 20 of the cap thereby firmly securing the socket to the goods.

A further feature of our construction is that the bead portion 16, which is formed 35 on the underside of the outer edge or periphery of the socket face plate is adapted to be crowded and forced into the surface of the goods to grip, bite and retain them and cause the goods to resist any tendency to be 40 pulled away or separated from about the neck portion of the socket.

We claim:

In a separable fastener, a socket member comprising a resilient front plate with a 45 central stud receiving opening and split through its face, the edge of said plate being rolled or bent over backward and the stock set inward from said edge forming an annular engaging rib said rib portion being 50 provided with a plurality of outward extending fingers forming a contracted neck portion, a device for securing said socket to the fabric comprising a cap member, an anvil contained in said cap and having a beveled 55 inner face against which the outer ends of said fingers are adapted to be forced to turn the same outwardly and clench said cap and socket member together.

In testimony whereof we affix our signatures in presence of two witnesses.

LUES REITER.
HARRY FULFORD.
